UNITED STATES PATENT OFFICE.

CHARLES A. NELSON, OF UTICA, NEW YORK, ASSIGNOR TO SAVAGE ARMS CORPORATION, OF UTICA, NEW YORK, A CORPORATION OF DELAWARE.

MAGAZINE-LOADER.

1,397,538.

Specification of Letters Patent.

Patented Nov. 22, 1921.

Application filed December 3, 1918. Serial No. 265,140.

To all whom it may concern:

Be it known that I, CHARLES A. NELSON, United States citizen, residing in Utica, New York, have invented the following-described Improvements in Magazine-Loaders.

The improvement provides means to expedite the process of transferring cartridges from a standard clip into the feed chute or cartridge chamber of a magazine loader such as is used for loading the magazines of machine guns, or directly into the magazine of that or any other class of fire-arm. Rifle cartridges are most efficiently handled in groups or rows of five or more held by their bases in a clip of well-known form by means of which they are kept in orderly arrangement for introduction into their place of use, being removed from the clip by pushing the row endwise out of engagement therewith. This invention consists in a construction of feed chute or analogous cartridge-receiving chamber specially correlated with the said clip to receive the same with the cartridges in it and automatically 25 eject it clear of the chute when the cartridges have been transferred. The invention is illustrated in the form at present preferred in the accompanying drawings, but without limitation to the particular detail illustrated.

Figure 1 is an elevation of the feed chute of a loader used for loading the rotary magazine of the well-known Lewis machine gun and having this invention applied;

Fig. 2 is a larger view of the chute, partly broken away and showing the ejector casing in section and the plunger-ejector thereof depressed by a cartridge clip;

Fig. 3 illustrates the same parts in different position and the clip ejected; and

Fig. 4 is a top plan of Fig. 3.

The illustrated loading machine is the same as that shown in my co-pending application Serial No. 115,128, filed August 16, 1916, and consists briefly of a cartridge chute 1 mounted on a base 4 and providing two opposing channels 2 and 3, the former for receiving the points of the cartridges and the latter the bases thereof. Cartridges introduced into the upper end of this chute descend therein under the control of a latch 5 and other members not necessary here to

be described, into the cartridge spaces of a rotary machine gun magazine shown at 6 and which will be recognized by those skilled in the art. This invention is applied to the chute of such a loader by affixing a small casing 7 to that side which constitutes the channel 3 for the cartridge bases, the said casing being formed with attachment 60 ears by which it embraces the edge of the chute and by which it is secured thereto in any suitable manner. Two small screws 8 are used for this purpose in the case illustrated but the manner of attaching or 65 mounting the casing on the chute is manifestly not of consequence; it can be integral with the chute if preferred or incorporated therein in various mechanically different manners. The casing contains a plunger 9 70 pressed upwardly by a spring 10 toward the receiving opening of the chute and carrying a lateral finger 11 which projects toward the path of the cartridges inside the chute but not into contact with them. 75 Where the casing is mounted as an attachment outside the chute as in the case illustrated, the finger 10 extends through a slot 12 cut in the end wall of the chute.

When the row of clip-held cartridges is 80 placed in position to enter the chute the holding clip will enter partway into the chute entrance until it seats by its two lateral lugs 13 in two notches 14 cut for the purpose in the upper end of the chute, and 85 in such entering movement the lower end of the clip will engage and depress the finger 11 against the pressure of the spring as indicated in Fig. 2. It will be observed that the notches and spring finger together constitute means for determining the position of the clip in the chute and the extent of its entrance therein, the principal function of the notches being to guide the clip into engagement with the finger and in the performance of this function the notches may be assisted more or less by the shape of the chute as a whole. The extent of entering movement may be determined either by the notches or by the finger.

If now the cartridges be forced downwardly or toward the chute with sufficient force to overcome the friction exerted on them by the clip spring, they will be forced

out of the clip and will enter the chute in the same orderly arrangement as they were held in the clip and when the last cartridge has left the clip the latter will be relieved of downward pressure and the spring 10 acting thereon will snap the finger upwardly and eject the clip clear of the chute as indicated in Fig. 3. The ejector thus functions automatically by the release of pressure on the clip which method is preferred to other means by which the ejector might also be caused to operate, because of its extreme simplicity and great reliability. The operator may thus deposit clipfulls of cartridges one after the other in the loader with great rapidity using only one hand for the operation, if need be, since the clip does not require to be handled and takes care of itself as above explained. A very material saving in time is thus effected over previous methods of transferring cartridges from clips

into the chambers in which they are to be used.

Claims:

1. In cartridge transferring mechanism, 25 the combination of a chamber formed to receive cartridges from a cartridge clip, and a member spring-pressed toward the receiving opening of the chamber, adapted to be depressed by engagement with the clip and rendered active to eject the clip by the disengagement of the last cartridge therewith. 30

2. In a magazine loading machine for loading separate magazines, a cartridge chute formed at its entrance end to receive a cartridge clip and provided with an automatically operating ejector for the empty clip. 35

In testimony whereof, I have signed this specification.

CHARLES A. NELSON.
